[57] **CLAIM**

The ornamental design for a hand-held vacuum cleaner, as shown and described.

DESCRIPTION

FIG. 1 is a perspective view of a hand-held vacuum cleaner showing our new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The crosshatch shading shown in all views is understood to repeat through the indicated area. The broken lines in FIGS. 2, 3 and 6 are understood to represent conventional stitching.
